CLAIM

The ornamental design for rotatable detachable head
for a weather resistant spot light, as shown and de-
scribed.

DESCRIPTION

FIG. 1 is a side elevational view of a rotatable, detach-
able head for a weather resistant spot light showing my
new design;

FIG. 2 is a top plan view thereof;

FIG. 3 is a bottom plan view thereof;
FIG. 4 is a perspective view thereof on a reduced scale;
The spot light housing and clamps for attaching the
head to the housing are shown in broken lines for illus-
trative purposes only.

FIG.1

FIG. 2

FIG. 3

FIG. 4
